UNITED STATES PATENT OFFICE.

PASCAL P. CHILD, OF ST. LOUIS, MISSOURI.

DESIGN FOR BARN-DOOR HANGER.

Specification forming part of Design No. 5,197, dated August 15, 1871.

To all whom it may concern:

Be it known that I, PASCAL P. CHILD, of the city and county of St. Louis and State of Missouri, have originated a certain new and useful Design for a Barn-Door Hanger, of which the accompanying drawing is a correct representation:

The drawing cannot be made to a particular scale, as the hangers are made of different sizes, varying chiefly from twelve to twenty-one inches in length.

The elements of usefulness in my hanger above those heretofore known are chiefly as follows: First, the face of the hanger is ribbed or cast with projecting ridges *r*, so as to increase the strength without any additional weight of metal, as the other parts may be cast thinner, and to give a handsome finish to said hanger. Second, the ears

e, containing the screw-holes are turned, the lower ones upward and the upper ones downward, so as to set the upper screw or bolt-holes downward from the upper edge of the door, to give them a firmer hold therein, the lower ears being turned upward to give a uniform finish to the hanger and to set the screw-holes upward from the lower edge of the horizontal tie-batten when one is used.

I claim—

The design for barn-door hanger, substantially as shown and described.

PASCAL P. CHILD.
